UNITED STATES PATENT OFFICE.

FREDERICK SAMUEL SCOTT, OF CHRISTCHURCH, NEW ZEALAND.

GAS OVEN.

Application filed February 16, 1928, Serial No. 254,726, and in New Zealand March 1, 1927.

This invention relates to gas ovens. The objects of the invention are, firstly to provide an improved construction for withdrawing the waste gases therefrom in such a manner that the said gases will be caused to thoroughly transverse the interior before escaping, and, secondly to provide means for pre-heating the air supplied to the burner to support combustion, thereby 10 effecting an economy in gas consumption.

In carrying these objects into effect the present invention consists briefly in the provision, at a point immediately to the inner side of the front of the oven and at a level 15 beneath the door opening, of one or more outlet-openings arranged to communicate by means of one or more passages extending horizontally, or virtually so, at the bottom of the oven, with a chimney 20 or vent-pipe arranged at the rear, and the provision in conjunction with the portion of the said vent-pipe connecting with the said passage or passages, of a jacket-space arranged to communicate between the atmosphere 25 at the exterior of the oven and a point in the interior of the latter adjacent to that at which the burner is located.

The arrangement is such that the heated gases rising from the burner at the back 30 portion of the interior of the oven become slightly cooled on reaching the top thereof and in consequence pass downward again at the front of the oven and enter the said outlet opening or openings from whence 35 such gases are delivered by the said horizontal passage or passages to the vent-pipe. This withdrawal of the gases serves to induce an in-flow of air through the said jacket-space to the burner, such incoming 40 air being heated in passing through the jacket space.

In order that the nature of the invention and its construction may be clearly understood, it will now be fully described and explained with reference to the accompanying 45 drawings, in which:—

Fig. 1—is a sectional elevation of a gas-oven, illustrating one preferred embodiment of the invention.

50 Fig. 2—is a plan-view of the same along the line II—II, Fig. 1, and wherein the positions of the outlet openings are indicated in dotted lines,

55 Fig. 3—is a sectional elevation along the line III—III, Fig. 1.

Fig. 4—is a plan-view of the front portion of the oven illustrating a slight modification of the arrangement shown in the preceding figures and wherein the positions of the door and the outlet openings are indicated in dotted lines, 60

Fig. 5—is a sectional elevation of the lower portion of the oven, illustrating a further modification.

Fig. 6—is a plan-view along the line VI—VI, Fig. 5, and,

Fig. 7—is a sectional elevation of the lower portion of the oven, illustrating a still further modification.

As here shown, 1 represents the oven structure, from which the shelves have been omitted, such oven being formed at its front side with the customary door 2 enclosing the door-opening 3 by means of which access is gained to the interior, while located at or 70 near the rear lower portion of such oven is the gas-burner 4 by means of which such oven is heated.

In one form of the construction, as here shown in Figs. 1, 2 and 3, there is provided 80 along the inner side of the front of the oven, at a level beneath the door opening 3, a horizontally disposed flue 5, through the upper side of which are formed openings 6 by means of which the waste gases from the 85 oven are adapted to enter such flue.

At its lateral sides the said oven is formed with passages 7 connecting at their forward ends with the ends of the flue 5 and extending to the rear of the oven where they 90 connect with a Y-shaped or T-shaped chimney or vent-pipe 8, the latter being preferably fitted with a regulating valve, as 9, turnable as by means of a crank or handle 10 for the purpose of varying the opening 95 area of the ventpipe and so governing the escape of the gases from the oven.

Two slides 11 may be provided, one in each of the passages 7 for the purpose of controlling the flow of the gases there-through such slides being operable from the front or sides of the oven.

In a slight modification of this construction, as shown in Fig. 4, the said flue instead of extending across beneath the door 105 opening, is divided to constitute a pair of pockets 12 arranged one in each of the front corners of the oven. The said pockets 12 will each be formed with one or more entrance openings 13 for admission of the 110

waste gases which are then conveyed by the lateral passages 7 to the vent-pipe 8 as in the previously described form.

In a further modification of the construction, as shown in Figs. 5 and 6, in lieu of the flue 5 or pockets 12, there is provided at the inner side of the front of the oven beneath the door-opening 3, a funnel-shaped intake member 14 having an upwardly facing mouth from whence such member diminishes in area to its lower end.

The said intake member 14 is preferably oblong or of other similar elongated form in plan and arranged with its longer sides parallel with the front of the oven in order that it may occupy as little space as possible in the interior of the oven.

Connecting with the said lower or smaller end of the said intake-member 14 is a horizontal, or substantially horizontal passage 15 which extends centrally across the bottom of the oven to pass beneath the burner 4 and connects with a vent-pipe 16 at the rear.

25. The bottom of the oven is enclosed by means of a horizontal plate 17 preferably arranged at a level corresponding approximately with that of the burner 4, the rear portion of such plate being preferably curved or swept downward sufficiently to pass beneath such burner.

The said plate will preferably be enamelled and arranged to rest upon flanges or projections, as 18, to permit of such plate being removed for cleaning purposes.

In a further modification of the construction, as shown in Fig. 7 the outlet-openings, as 19 will be formed through the plate 17 and at an interval beneath which a second 40 horizontal plate 20 will be provided to fit closely with the walls of the oven and thus constitute a chamber or passage 21 through which the waste gases entering through the openings 19 will be conveyed to a vent-pipe 45 as 22.

As already mentioned there is provided in conjunction with the portion of the vent-pipe connecting with the said horizontal passage or passages, a jacket-space as 23 50 communicating with the atmosphere as at 24 and connecting as by means of an opening 25 with the interior of the oven at a point adjacent to the burner 4, the ar-

rangement being such that air entering such jacket-space will be heated by the vent-pipe 55 before passing to the interior of the oven.

This jacket-space may be provided as shown in Figs. 1, 2 and 3 by providing a wall as 26 spaced at an interval from the vent-pipe or as shown in Figs. 5, 6, and 7 60 by providing walls as 27 to connect between the vent-pipe and the wall of the oven.

In operation the heated gases rising from the burner 4 at the back portion of the interior of the oven will become slightly 65 cooled on reaching the top and will in consequence pass downward again at the front portion of such oven and enter the said outlet openings from whence such gases will be conveyed by means of the horizontal passage or passages to the vent-pipe, such withdrawal of the gases serving to induce an inflow of air through the jacket-space, where it becomes heated by the vent-pipe, to the portion of the interior of the oven in which 70 the burner is situated.

I claim:

1. In a gas-oven having a door opening at the front and a gas-burner disposed in the rear lower corner of such oven, outlet-openings for waste gases arranged immediately to the inner side of the front of the oven at a level beneath said door-opening, and substantially horizontal passages at the bottom of the oven communicating with said outlet openings and with a vent-pipe at the rear of the oven.

2. A gas-oven as defined in claim 1 a jacket-space being provided in conjunction with the portion of said vent-pipe connecting with said horizontal passage or passages, said jacket-space communicating between the atmosphere at the exterior of the oven and the portion of the interior of the latter adjacent to the burner to pre-heat the air supplied to support combustion.

3. A gas-oven as defined in claim 1, the lower end of said oven being enclosed by a plate removably supported, said plate being arranged approximately at the level of the burner and having its rear portion curved downward to lie lower than the openings of said burner.

In testimony whereof I have hereunto affixed my signature.

FREDERICK SAMUEL SCOTT.
